SPRING ASSEMBLY STRUCTURE

Kent D. Steadley, Carthage, Mo.

Application December 11, 1933, Serial No. 701,909

4 Claims. (Cl. 5—269)

The present invention relates to the manufacture of spring assemblies entering into the construction of bed bottoms, cushions and the like, wherein coil springs, arranged in parallel rows, have the springs standing opposite each other connected by long wire spirals of small size. It has for its object to so unite the springs of two adjacent rows that they may have a hinging action relative to each other that will be sufficiently free, but without undue looseness, and that it be practically noiseless when in use. The connection of the springs according to the present invention may be expeditiously and accurately accomplished largely by the use of machinery, and the uniting spirals employed are of relatively small size, since no single coil of such spiral is called upon to surround or embrace more than one strand of the springs which it unites, thus effecting a saving in the cost of material employed.

That my invention may be the better understood I have illustrated in the accompanying drawings two different embodiments thereof.

Figure 1 is a plan view of a section of a spring bed mattress made according to the present invention;

Figure 2 is a sectional view taken on the line 2—2 of Figure 1;

Figure 3 is a transverse sectional view on the line 3—3 of Figure 2;

Figure 4 is a plan view of a section of a spring bed mattress showing a different embodiment of the present invention from that illustrated in Figure 1;

Figure 5 is an edge view of the showing in Figure 4, and

Fig. 6 is a sectional view taken on the line 7—7 of Figure 4.

Referring particularly to Figures 1 to 3 of the drawings 2, designates the coil springs which are united to form the desired spring assembly. They are arranged in parallel rows, individual springs standing opposite to each other and being connected, preferably at both top and bottom by spiral coils of wire 3. The terminal coils of the springs are formed to have offset portions with which the spirals engage, such offsets being constructed and assembled in a novel manner to improve the connections between the springs.

In this specification the connections of the springs at one end—the upper—only will be described, it being understood that the connections at the opposite end are similar, so that the spring assembly may be reversible, either face being used uppermost as desired. It should also be under-

stood that certain terms employed in this specification, such as "plane", "straight", "vertical", "parallel", "horizontal", etc., are not used in an absolute sense but rather in an approximate or relative sense.

Referring again to the drawings it will be seen that one of a pair of springs to be united has its end coil or convolution formed with an offset portion that is located in the horizontal plane of the coil of which it is a part. Each of such offsets has a central main straight portion 4 and shoulders 5 uniting the portion 4 to the main body of the coil of the spring. The other spring of the united pair is formed with an offset, the central main straight portion, 10, of which is located in a horizontal plane to one side of the plane of the coil or convolution of which it is a part, being a little below it in the arrangement being described. This offset has laterally extending shoulders 7, similar to the shoulders 5 of the other offset, already described, which merge into short straight portions 8 that are in line with each other, but spaced apart. At the ends of the straight parts the wire of the offset is bent downwardly, forming short vertically disposed shoulders 9, between and uniting which is the main central portion 10 of the offset, the length of which is a little greater than the main central portion 4 of the offset of the opposite spring. When the two springs are to be united, the two offsets with which they are respectively formed are brought together as represented in the drawings and united by a connector, consisting of a small bore spiral or helix of wire, 3, that is caused to encircle portions of each offset, no single coil, however, of the spiral embracing and encircling more than one wire or strand. It will be seen that the two main central portions, 4 and 10, of the two offsets are parallel with each other, but are located in different horizontal planes and are not in contact. The longer of these two parallel portions, 10, is below the part 4. It will also be seen that the short straight portions 8, of one offset are in the same horizontal plane as the central portion 4 of the other offset and are in line therewith, one at each end thereof. When thus arranged the spiral 3 that unites the offsets of the two springs has one or more of its coils encircling each of the short straight portions 8 of one spring and several of its coils encircling the central part 4 of the offset of the other spring. When thus arranged and united the spiral at no point encircles more than one wire at a time, and the portions of the offsets with which the spiral directly engages and which

- it unites are not crossed or overlapped, but rather are in alinement with each other. This arrangement has several advantages: a smaller spiral 3 can be used than is required when the spiral has 5 to encircle in its course, two or more connected parts by a single one of its coils; and the parts of the springs with which the spiral engages, being in line with each other, the hinging together of the two rows of springs by means of the spiral 10 is improved, and the parts of the offsets of the united springs are not at any points in rubbing engagement one with the other, thus reducing to a minimum the tendency to squeaking, and other noises produced by the rubbing of parts when the 15 spring assembly is subjected to pressures in use. The two central portions of the offsets of a pair of united springs, being located in different horizontal planes and one directly over the other and but one of them being engaged by the uniting 20 spiral, the hinging action as the springs are forced downwardly or upwardly at the joints is free, but without undue looseness of the parts within the coils of the spirals.
- In that form of the invention illustrated in Figures 4 to 6, the two springs in adjacent rows to be united are designated 20 and 20'. The spring 20 is in construction with diametrically opposite offsets in its end coils identical with the offsets 25 which have already been described, these being located in the plane of the end coil of the spring and designated 40. The spring 20', however, differs from spring 20 in the construction of the offsets with which its end coil is provided. Thus, the main central portion 100 of this offset is 30 longer than the main central portion 40 of the offset of spring 20, and it is located in a different horizontal plane,—being below,—but separate from, close to and parallel with the part 40. At each end of the main central portion 100 of the 35 offset are vertical shoulders 90 uniting it with portions 80 that are located in the same horizontal plane as is the part 40 of the opposing offset and opposite to the ends thereof. These parts 40 of the offset are connected with the normal curved portion of the end coil by shoulders 50. When the springs such as just described are to 45 be hingedly united by spiral 3 they are brought together with the offsets of the respective springs in the relationship illustrated in Figures 4 to 6, the main central portions 40 and 100 thereof being directly one above the other, but out of contact, while the portions 80 of the offset of spring 20' are opposite the ends of, and in line with, the main central part 40 of the offset of the other 55 spring. When thus arranged the spiral 3 encircles with a plurality of its coils, the part 40 of the offset of spring 20 while the parts 80 of the other offset are each encircled by a single turn or coil of the spiral. This insures a freely 60 hinging union of the springs, without undue looseness of parts and insures entire freedom from noise due to the rubbing together of the united parts of the spring when the spring structure is in use. It will be seen, particularly by reference to Figures 5 and 6, that when the springs 65 20, 20' are united into a spring structure or assembly the upper ends of the springs 20, including the end coils or convolutions thereof, are located in a horizontal plane a little higher than 70 the end convolutions of the springs 20'. This

difference in height of the springs is practically negligible in the use of the structure as a support for a mattress. The result illustrated and just referred to may be secured by making the springs 20' a little shorter than the springs 20, or by putting springs 20' under a little compression incident to the manner of uniting the springs which has been described, and illustrated in the drawings.

It will be observed that at each connection of 80 adjacent springs there are employed two constructions of offsets formed in the coils of the united springs and that each spring carries two offsets which are arranged diametrically opposite to each other. The two offsets of any one 85 spring may be identical as represented in Figure 4 or they may be different as shown in Figure 1 where one form of offset is formed in the coil at one side of the spring and the other form of offset opposite thereto at the other side of the 90 spring.

Having described the invention, what is claimed is:

1. A spring assembly in which coil springs are arranged in parallel rows, and wherein the 100 springs are also in transverse alinement, those opposite each other in such alinement being united, characterized by the united springs being formed each with an offset portion, that of one spring having a main central section and that of the 105 other spring having two relatively short alining sections united by a central longer section, which is parallel to the short sections, said long section being in a plane below the alined short sections, and the short sections being located in line with and respectively opposite to the ends of the 110 straight section of the opposite offset and a small bore helix uniting the said springs by engagement with said alining parts of the opposite offsets.

2. In a spring assembly wherein coil springs located side by side in alinement are united to form a spring structure, two coil springs one formed with an offset located in the plane of its end coil or convolution, and the other spring with 120 an offset comprising a central portion that is in a plane below that of its end coil, vertical shoulders at the ends of said central part, and laterally extending parts in the plane of the end coil or convolution and uniting the said vertical shoulders with said end coil, the central portions of the offsets of the two springs being of unequal length and that of the first mentioned spring being disposed above the other, but not in contact therewith, and a spiral uniting the offsets of said 130 springs by engagement with the central part of the first offset and the laterally extending parts of the second offset.

3. A spring assembly such as described in claim 1 and further characterized by the described two 135 relatively short aligning sections being joined to the central longer section by other relatively short sections which extend downwardly relative to the top coil of the spring carrying them.

4. A spring assembly such as described in claim 1 and further characterized by the described two 140 relatively short aligning sections lying in a plane above the top coil of the spring carrying them.
